UNITED STATES PATENT OFFICE

163,685

SCRATCH-PAD SUPPORT OR THE LIKE

Pearl B. Foster, San Francisco, Calif.

Application April 25, 1950, Serial No. 9,460

Term of patent 14 years

(Cl. D74—1)

To all whom it may concern:

Be it known that I, Pearl B. Foster, a citizen of the United States of America, residing in the city and county of San Francisco, and State of California, have invented a new, original, and ornamental Design for a Scratch-Pad Support or the like, of which the following is a specification, references being had to the accompanying drawing, forming part hereof.

The figure is a front perspective view of a scratch-pad support or the like, showing my new design.

I claim:

The ornamental design for a scratch-pad support or the like, as shown.

PEARL B. FOSTER.
